UNITED STATES PATENT OFFICE.

FREDERICK M. FURBER, OF BEACHMONT, MASSACHUSETTS, ASSIGNOR TO UNITED SHOE MACHINERY CORPORATION, OF PATERSON, NEW JERSEY, A CORPORATION OF NEW JERSEY.

STOCK-TREATING MACHINE.

Application filed October 10, 1921. Serial No. 506,859.

This invention relates to machines for performing finishing operations upon boot or shoe parts, and is herein illustrated as embodied in an upper seam-pressing or rubbing 5 machine of the type described in United States Letters Patent No. 1,570,057, granted Jan. 19, 1926, in the name of the present applicant.

In machines of this type, two important 10 considerations are the rapidity and certainty with which the sides of the seam are separated or opened, and the permanence of the "set" given the seam as the sides are pressed or flattened down; and an object of the present 15 invention is to improve the operation of seam-pressing machines in both respects, as herein-after explained.

In accordance with this object, a feature of 20 the invention is to be found in the provision of a novel moving seam-opening device, as distinguished from the stationary or drag "plows" ordinarily used. This results in a positive opening of the seam, and eliminates the tendency toward jamming which, especially 25 to inexperienced operators, is difficult to avoid with seam-opening devices of the drag type. In the illustrated machine, the novel seam-opening plow member is mounted on the feed hammer, and is given thereby a 30 movement in an orbital path enabling it most effectively to open successive increments of a seam guided thereto by improved seam-guiding members. Thus jamming is impossible, as the opening of successive increments of the 35 seam forms a series of entirely separate operations.

To improve the permanence of the set given the seam, I provide means for heating the work-feeding and pressing hammer, and improve 40 the action of the hammer itself by mounting it relatively to a roller work-support so that its sharply-defined front edge comes just at the line of tangency to the surface of the work-support. Thus the hammer 45 acts on successive narrow increments of very small area with a relatively heavy pressure, resulting in a "biting" as well as a pounding action on the seam which, especially with the aid of heat, imparts a high degree of permanence 50 to the set of the flattened seam. The seam-opening plow is preferably yieldingly mounted, so as not to interfere with this biting action.

The invention also contemplates the use of an improved moistening device, and this and other features of the invention, including novel elements and combinations of parts, will be apparent from the following description of an illustrative embodiment of my invention shown in the accompanying drawings, 60 in which

Fig. 1 is a longitudinal cross-section of such a machine;

Fig. 2 is a perspective of the operating parts;

Fig. 3 is a section on the line 3—3, Fig. 1, showing the operation of the seam guides;

Fig. 4 is a section on the line 4—4, Fig. 1, showing the mounting of the hammer;

Fig. 5 is a view of an alternative form of 70 seam-opener, embodying improved means for moistening the seam.

The machine comprises generally a casing 10, inclosing the operating mechanism, and in which there are formed suitable bearings for a drive shaft 12. This shaft carries a bevel gear meshing with a bevel gear on a vertical shaft, which is geared to a horizontal shaft in the base of the machine. This horizontal shaft in turn carries a bevel gear meshing 75 with a bevel gear slidingly keyed to a vertical shaft in the front portion of the machine which in turn carries a bevel gear driving a rotary work-supporting feed wheel 14. The feed wheel 14 and its drive shaft are carried by a vertically-movable slide arranged to be depressed by a treadle against the resistance of an uplifting spring. A driven shaft 18 is continuously rotated from shaft 12 by a belt indicated by broken lines in Fig. 1. These 80 elements may be, and are illustrated as being, the same as corresponding parts fully described in my above-identified prior application.

A seam is guided into the machine by members 20 each having a portion engaging one side of the seam, and another portion mounted in bearings in a plate 22 which can be adjusted vertically by screw 24 and clamped by clamp-nut 26. Arms 28 are carried by the upper portions of members 20, and are connected by a spring 30, tending to twist the lower ends thereof into engagement with the seam. As best shown in Fig. 3, an adjustable stop 32 is provided for adjusting the 100 position of guides 20.

The feeding of the work is accomplished by co-operation of support 14 with a feed hammer 40, pivotally mounted on links 42 carried by casing 10, and given an orbital or 5 four-way motion by an eccentric 44 on shaft 18. As shown in Fig. 4, the work-engaging portion 46 of the hammer is secured thereto by a bolt 48 of such a shape as to make it impossible to mount the hammer in the machine in reversed position.

In order to provide the above-described biting action of the hammer on the seam, it is provided with a relatively sharp forward edge 50 coming substantially at the line of tangency to the surface of support 14. Thus the pressure is concentrated on a narrow strip immediately adjacent the line of tangency, and is much more effective than if spread over the usual comparatively large area.

20 The hammer is heated by an electric unit in a stationary member 52, slotted at its forward end to embrace the work engaging portion 46.

This hammer is driven at a speed greater 25 than the peripheral speed of work support 14, so that it delivers a wiping or ironing blow on the work, providing a very heavy pressure on a narrow area which is moved progressively along the seam. This is found 30 much more effective than ironing in such a manner as to distribute the same heavy pressure over a relatively large area. As the work moves more slowly than the hammer, each successive increment of the seam is 35 wiped or ironed down by a plurality of blows of the hammer.

The seam is opened by a plow member 60, seated on a forwardly-projecting portion of 40 the hammer, and guided by a pin 62 passing therethrough and secured at its opposite ends in the hammer. It is yieldingly urged downward against its seat on the hammer by a spring 64. The plow member is given a clawing or scratching motion by the operation of 45 the hammer, so that it is moved periodically into work engaging position and operates to open successive increments of the seam in a novel and highly-efficient manner. During the biting or seam-compressing action of edge 50, the plow is free to yield upwardly.

In operation, the work is presented to the machine, with the seam between guides 20. Successive increments of the seam are opened by member 60, and thereafter flattened by 55 the heated hammer. While successive increments are of small area, the machine operates at a high rate of speed, and the resulting speed of feeding the work is as great as is desirable. As is well-known to those skilled in the art, it is necessary to withdraw certain kinds of closed seams by depressing work-support 14 by means of treadle rod 16.

In operating on some classes of work, it is desirable to introduce water, steam, melted 60 wax, starch, or a similar fluid, between the

sides of the seam, as this aids in setting the seam when pressed, especially if pressed with a heated member as in the present case, in a manner which is well-known and need not be here discussed. In my prior United States Letters Patent No. 1,295,152, granted Feb. 25, 1919, I have shown and claimed a device adapted for introducing such fluids in a machine having a seam-opener of the drag type. In Fig. 5 herein is shown an illustrative form 70 of such apparatus as adapted for the present machine.

In this improved form, the seam-opening device 60 is provided with a passage-way to which fluid is delivered, preferably under pressure, from any suitable source, through a flexible tube 70. The delivery of the fluid is controlled by a valve including a conical portion 72, normally held against its seat by gravity and by the pressure of the fluid, and a stem portion 74, which engages the work to open the valve. A set-screw 76 is provided, adjustably to limit the extent to which the valve may open and thereby to control the amount of fluid delivered on the work.

While my invention has been described as embodied in an illustrative machine of the same general type as those disclosed in my said prior application, it is not my intention to limit its scope thereby, or otherwise than by the terms of the appended claims.

Having described my invention, what I claim as new and desire to secure by Letters Patent of the United States is:

1. In a seam pressing machine, in combination, a roller support for a piece of work having a seam, yieldingly mounted members to engage opposite sides of a seam and guide it as the work passes on to the support, a hammer to feed the work across the support and press the seam thereagainst, and a plow member mounted on the hammer to scratch or claw open the seam as it leaves the guide members.

2. In a seam pressing machine, in combination, a seam support, a member to flatten a seam thereagainst, and a seam opening device yieldingly mounted on the seam-flattening member.

3. In a seam pressing machine, in combination, members yieldingly to engage and guide the opposite sides of a seam, a member movable relatively thereto to flatten the seam, and a plow member carried by the movable member to open the seam as it leaves the guide members ready to be flattened.

4. In a seam pressing machine, in combination, a support for a seam, and a device movable relatively thereto in a closed path and having a pounding portion to press a seam against the support and a plow portion mounted thereon so as to yield relatively thereto and arranged to open the seam ready for pressing.

5. In a seam pressing machine, in combina-

- tion, a support for a seam, and a device movable relatively thereto in a closed path and having a pounding surface to press a portion of a seam against the support, and a plow 65 surface to open a further portion of the seam ready to be pressed.
6. In a seam pressing machine, in combination, a support for a seam, a device movable relatively thereto and comprising a part to flatten an increment of a seam against the support and another part to open a further increment of the seam ready to be flattened, a 70 rotary shaft, and connections from the shaft relatively to remove the support and said device to open and flatten successive increments of the seam.
7. In a seam pressing machine, in combination, a support for a piece of work having a seam, an intermittently-effective power-driven hammer movable to flatten a seam against the support, and a seam-opening device carried by the hammer and constructed and arranged to open the seam ahead of the hammer. 75
8. For use in a seam pressing machine, a seam-pressing hammer having a relatively movable seam-opening device carried thereby. 80
9. In a machine of the class described, in combination, means to act on a seam after it has been opened, and means to present a seam thereto including a member intermittently movable to open the seam in successive increments. 85
10. In a machine of the class described, in combination, a member to separate the sides of a seam, and means to move said member in a cycle to open successive increments of the seam. 90
11. In a machine of the class described, in combination, a member to separate the sides of a seam, and means to move said member in a closed path to open successive increments of the seam by a clawing or scratching motion. 95
12. In a machine of the class described, in combination, members to support and guide the sides of a seam, and a member bodily movable relatively thereto to open successive increments of a seam guided thereby. 100
13. In a machine of the class described, in combination, members to support and guide the sides of a seam, and a member movable relatively thereto to open successive increments of a seam guided thereby. 110
14. In a seam pressing machine, in combination, a support for a seam, a hammer movable to flatten a seam thereagainst, and a stationary heated member slotted at one end to embrace the hammer and transmit heat there- 115 to. 120
15. In a machine of the class described, in combination, a movable work engaging member, a stationary member having a slotted end embracing the sides of the movable member, and an electric heating unit within and supported by the stationary member so that heat will be transmitted through the stationary member to the work-engaging member. 125
16. In a seam pressing machine, in combination, a support for a seam, a hammer movable in one direction in engagement with a seam on the support to feed it over the support while pressing it thereagainst and arranged to be lifted entirely out of engagement with the seam when returning in the reverse direction, and means to heat the hammer to set the seam as it is flattened. 75
17. In a pressing machine, in combination, a support for the work, a movable hammer to press the work thereagainst, and a stationary heated member substantially in engagement with the outer surface of the hammer to transmit heat thereto to secure simultaneous action of heat and pressure on the work. 80
18. In a seam pressing machine, in combination, a roller support for a seam, and a hammer to flatten a seam thereon and feed it thereover, the seam-engaging surface of the hammer being approximately tangent to the surface of the support, with the forward edge of the hammer at the line of tangency, in order that the hammer shall act on successive increments of small area by a biting action. 85
19. In a seam pressing machine, in combination, a support for a seam, and a hammer to flatten a seam thereon and feed it thereover, said support and said hammer being constructed and arranged so that the pressure on the seam will be greatest at one edge of the hammer, in order that the seam shall be flattened by co-operative action of the support and the hammer in biting into successive increments thereof. 90
20. In a seam pressing machine, in combination, a rotary support for a seam and a hammer to flatten successive increments of a seam thereon and to feed the seam thereover, the hammer being constructed and arranged to approach the surface of the support most nearly at its foremost edge, so that it has a biting action on the seam. 100
21. In a seam pressing machine, seam guides comprising members each having a part to engage one side of a seam and another part substantially at right angles thereto to form a pivot about which the first part turns, spring means twisting said members about the pivoted parts and a manually-adjustable stop to limit the action of the spring means in twisting the seam-engaging parts toward one another. 110
22. In a stock-finishing machine, in combination, a hammer to press a crease in a piece of stock to render it permanent, and a member yieldingly mounted on the hammer for turning the edge of the stock to prepare the crease for pressing. 120
23. In a stock-finishing machine, in com-

bination, a member movable back and forth parallel to the edge of a piece of stock to turn the edge upon itself, and a hammer movable simultaneously with said member to give a wiping blow to the stock to press the crease formed by so turning the edge.

24. In a stock-finishing machine, in combination, a support for a piece of stock, means to turn the edge of the stock upon itself, a hammer movable to press the turned edge and to feed the stock across the support, and a heated stationary member engaging the hammer to transmit heat thereto to set the pressed edge.

15 25. In a stock-treating machine, in combination, a mechanically-actuated support to engage and feed a piece of stock, a pressing member to engage a narrow area of the stock with a pressure which is heaviest at its forward end, and means to move said member relatively to stock fed by the support to move the narrow area of pressure along the stock.

26. In a stock-treating machine, in combination, a mechanically-actuated support to engage and feed a piece of stock, a pressing hammer to engage a narrow area of the stock with a pressure which is heaviest at its forward end, and means to actuate the hammer to deliver wiping or ironing blows on the work fed by the support.

27. In a stock-treating machine, in combination, a support for a piece of stock, and a hammer to deliver wiping or ironing blows on stock supported thereby, said support and said hammer being arranged to co-operate in feeding the stock at such a rate that each successive increment thereof receives a plurality of blows from the hammer.

28. In a stock-treating machine, a hammer constructed and arranged to engage a narrow area of a piece of stock and to bear most heavily on the stock at its forward edge, and means to move the hammer to deliver a series of wiping or ironing blows on the stock with a biting action.

29. In a stock-treating machine, in combination, means for feeding a piece of stock, means intermittently operable to deliver successive portions of fluid on the stock, and means to press stock on which fluid has been delivered thereby.

30. In a stock-treating machine, in combination, means intermittently operable to deliver successive portions of fluid on definite areas of a piece of stock, means to present stock thereto in such a manner that successive areas overlap to provide continuous treatment of the stock by the fluid, and means to press stock on which fluid has been delivered thereby.

31. In a stock-treating machine, in combination, an instrumentality to operate on a piece of stock, means to prepare the stock for the action thereof including a fluid-deliver-

ing device comprising a valve to be actuated by engagement with the seam, and mechanism to actuate said means in a manner to bring the valve periodically into engagement with the work.

32. In a seam pressing machine, in combination, a support for a piece of work having a seam, a member movable to flatten the seam against the support, a seam opening plow periodically movable into work engaging position, and means carried by the plow and actuated by engagement with the work for intermittently delivering fluid on the seam.

33. In a seam pressing machine, in combination, a rotary support for a piece of work having a seam, a reciprocating hammer co-operating with said support to feed the work and flatten the seam, means for actuating said support and said hammer, means for transmitting heat to the hammer, and a seam opening plow mounted on the hammer.

34. In a seam pressing machine, in combination, a support for a piece of work having a seam, a movable pressure applying device for flattening a seam against said support, and an electrically heated member arranged for sliding engagement with said device to transmit heat thereto.

35. In a seam pressing machine, in combination, a rotary support for a piece of work having a seam, a hammer for flattening a seam against the support, a driving shaft, driving connections between the shaft and the support and between the shaft and the hammer, and means movable with the hammer for opening the seam ahead of the hammer.

36. In a seam pressing machine, in combination, a support for sustaining and feeding a piece of work having a seam, a member movable toward and from the support and back and forth with respect to the line of feed of the work for pressing the sides of the seam against the support, and a device arranged to partake of the back-and-forth movements of the pressing member for opening the seam.

37. In a seam pressing machine, in combination, a support for sustaining and feeding a piece of work having a seam, a hammer movable toward the support to press the sides of the seam and forwardly in the direction of work feed to co-operate with the support in feeding the work, and a seam opening member arranged to partake of all of said movements of the hammer.

38. In a seam pressing machine, in combination, means for sustaining and feeding a piece of work having a seam, a hammer movable toward and from the seam and back and forth with respect to the line of feed of the work, and a member movable in unison with the back-and-forth movements of the hammer for spreading the sides of the seam.

39. In a seam pressing machine, in combination, means for sustaining and feeding a

piece of work having a seam, a hammer movable toward and from the seam and back and forth with respect to the line of feed of the work, a member movable in unison with the 5 back-and-forth movements of the hammer for spreading the sides of the seam, and yielding connections between the hammer and said member for moving the latter toward the work during the movement of the hammer 10 toward the work.

40. In a seam pressing machine, in combination, a rotary support for sustaining and feeding a piece of work having a seam, a hammer movable toward and from the seam 15 and back and forth with respect to the line of feed of the work, and a member movable back and forth and in a direction away from the

seam in unison with the hammer and arranged to partake yieldingly of the movement of the hammer toward the seam. 20

41. In a seam pressing machine, in combination, a rotary support for sustaining and feeding a piece of work having a seam, a seam pressing hammer movable toward and from the seam and back and forth with respect to the line of feed of the work, a seam opening member movable back and forth in unison with the hammer, means on the hammer for moving the opening member from the work, and a spring for moving the opening member toward the work. 25 30

In testimony whereof I have signed my name to this specification.

FREDERICK M. FURBER.

CERTIFICATE OF CORRECTION.

Patent No. 1,701,845.

Granted February 12, 1929, to

FREDERICK M. FURBER.

It is hereby certified that error appears in the printed specification of the above numbered patent requiring correction as follows: Page 1, line 62, for the misspelled compound word "cros-section" read "cross-section"; page 3, line 14, claim 6, for "remove" read "move"; and that the said Letters Patent should be read with these corrections therein that the same may conform to the record of the case in the Patent Office.

Signed and sealed this 15th day of October, A. D. 1929.

(Seal)

M. J. Moore,
Acting Commissioner of Patents.
